ATTORNEY.

UNITED STATES PATENT OFFICE.

CHARLES C. WARD AND CHARLES W. WARREN, OF MOUNT VERNON, OHIO.

FENCING.

SPECIFICATION forming part of Letters Patent No. 434,965, dated August 26, 1890.

Application filed January 10, 1890. Serial No. 336,512. (No model.)

To all whom it may concern:

Be it known that we, CHARLES C. WARD and CHARLES W. WARREN, citizens of the United States, residing at Mount Vernon, in the county 5 of Knox and State of Ohio, have invented a certain new and useful Improvement in Fencing, of which the following is a specification.

Our invention relates to the improvement of wire fencing, and has particular relation to 10 that class of wire fencing in which the horizontal parallel wires are connected at intervals with vertical wires or pickets.

The objects of our invention are to provide 15 a fence of this class which shall be of simple construction and inexpensive and of a durable and neat form, and to provide an improved connection of the parallel horizontal wires and the vertical wires or pickets, which, aside from ordinary posts, comprise the fence. 20 These objects we accomplish in the manner illustrated in the accompanying drawings, in which—

Figure 1 is a view in elevation of one side 25 of a portion of our improved fence, which, for convenience, we will term the "front side." Fig. 2 is a view in detail of the rear face of one of our improved clinching or connecting pieces, showing two wires connected thereby. Fig. 3 is a side elevation of the same, and Fig. 30 4 is a face view of a modified form of a binding-plate.

Similar letters refer to similar parts throughout the several views.

A represents the horizontal parallel wires 35 of fence, and B the vertical wires thereof, which cross said wires A at desired intervals at right angles therewith, and which, when connected therewith, serve to strengthen the fence and hold the wires A in proper alignment.

c represents a binding-plate, which, as 40 shown, has the general form of a metallic washer, and consists in a disk of metal provided with a central opening, which may be square, as shown, or circular.

d represents a metallic clinching or connecting cap, which consists of two or more (preferably four) separated prongs or fingers

d', which are formed with and project outwardly from a solid base or end. 50

In connecting the wires A and B one of the binding-plates c is placed flatly against the horizontal wire at the junction of said wires in such manner as to cause the central opening of said plate to form a frame for the contact-points of the two wires. The cap d is then so placed as to cause its prongs d' to enter the central opening of the binding-plate on opposite sides of the wires A B and cause its solid head or end to bear firmly against the vertical wire. The ends of the prongs d', which are thus made to project through the plate-opening, are, as shown, then bent back or clinched against the rear face of the plate, thus clamping the wires firmly together and 60 providing a flat bearing for the clinch-prongs. The spaces between the prongs adjoining their head are of such size as to cause the wires to fit closely therein when clamped as above described, thus preventing play or 65 looseness between the parts. The pressure of the vertical wire against the horizontal wire exerted by the cap will tend to produce a slight outward bend of the vertical wire, as shown at x in Fig. 3 of the drawings, thus providing in said vertical wire a slight offset or 70 seat for the horizontal wire and aiding in assuring the connection of said wires. 75

From the construction herein shown it is obvious that a strong and durable connection 80 of the two sets of wires is attained by simple and comparatively inexpensive means. It will also be observed that with clamping-tools properly constructed the above-described connection may be made with rapidity and ease, 85 and that each connection being made separately one of said connections may be replaced or repaired without interfering with the other.

As shown in Fig. 4 of the drawings, we may 90 omit the large central hole in the binding-plate and substitute therefor a slotted opening for the reception of the prongs of the cap. Said plate might also be in the form of an ordinary ring without altering the principle of 95 our invention.

Having now fully described our invention, what we claim, and desire to secure by Letters Patent, is—

In a wire fence, the combination, with the 5 intersecting wires A B, of binding-plate *c*, having one or more openings therein, and clinching-cap *d*, having prongs *d'*, adapted to be inserted within said plate opening or open-

ings on opposite sides of the wires A B and clinched against the face of said plate, substantially as described.

CHARLES C. WARD.

CHARLES W. WARREN.

In presence of—

JOHN E. RUSSELL,

RAYMOND BEDELL.
